Primary Examiner — Susan Bennett Hattan*Assistant Examiner* — Brett Miller(74) *Attorney, Agent, or Firm* — Patterson + Sheridan, LLP(57) **CLAIM**

I claim the ornamental design for a carry strap bracket for a camera, as shown and described.

DESCRIPTION

FIG. 1 is a perspective view of a carry strap bracket for a camera.

FIG. 2 is a top view of the carry strap bracket

FIG. 3 is a side view of the carry strap bracket, the opposite side being a mirror image thereof.

FIG. 4 is a bottom view of the carry strap bracket.

FIG. 5 is a back view of the carry strap bracket.

FIG. 6 is a back view of the carry strap bracket; and,

FIG. 7 is a perspective view of the carry strap bracket

mounted to a camera.

The broken lines in the figures depict the bounds of the

claimed design and form no part thereof.
